UNITED STATES PATENT OFFICE.

LOUIS STRAUB, OF DENVER, COLORADO.

TOWEL-RACK.

1,281,695.

Specification of Letters Patent. Patented Oct. 15, 1918.

Application filed April 12, 1917. Serial No. 161,427.

To all whom it may concern:

Be it known that I, LOUIS STRAUB, a citizen of the United States, residing at Denver, in the county of Denver and State of Colorado, have invented certain new and useful Improvements in Towel-Racks, of which the following is a specification.

This invention relates to towel racks of the type used principally in public lavatories, to provide in connection with a suitable holder, a number of separately accessible towels which are locked against unauthorized removal.

A rack of the character specified has been shown and described in my Letters-Patent No. 1038984, issued September 17, 1912 and it is the primary object of the present invention to provide certain improvements which greatly advance the usefulness and practicability of the device.

Principal among these improvements is a towel-holding link which is separable from the stationary part of the rack to which it is normally secured by lock-controlled means.

The link when fastened on the stationary element of the invention holds the towels in a position for ready separate use, and when removed from the element, is employed to carry the towels collectively to and from the laundry or other place of supply.

The above and other objects all of which will fully appear in the course of the following description, are attained by the combinations of parts and features of construction illustrated in the accompanying drawings in the various views of which like parts are similarly designated, and in which—

Figure 1 represents a face view of my improved towel rack in its operative position;

Fig. 2 a section taken along the line 2—2, Fig. 1;

Fig. 3, an elevation of the towel holding link separate from the rack, with the locking means in the position they occupy when the link and the therewith connected towels are carried from one place to another.

Referring more specifically to the drawings, my invention comprises a stationary element composed of a pair of brackets which may be secured to a wall or other suitable support, a shelf 3 rigidly fastened upon the brackets, and a hook 4 for the suspension of the towel link 5.

The hook has at its lower end an upwardly projecting stud 6 and the shelf has in alignment therewith an aperture 7 to receive the end of a towel-link suspended from the hook as will hereinafter be described.

U-shaped apertured plates 8 fastened beneath the shelf are provided to increase the rigidity of the hook and the end of the link inserted through the opening 7.

The towel holding device of my invention consists of a rod bent in the form of an oblong link the ends of which are separated to provide an entrance 9 for the edge of the shelf when the link is placed upon the stationary rack or removed therefrom.

The end of the rod of which the link is composed, below this entrance, is bent into a laterally projecting eye 10 made to fit upon the upwardly projecting stud on the hook suspended from the shelf and the opposite end 12 of the rod is aligned with this eye to enter the opening 7 in the shelf which as stated hereinbefore is aligned with the stud.

A pad-lock 13 is attached at the end of a chain 14 which at its opposite end is securely fastened to the link adjacent its laterally projecting eye, and the stud on the hook has adjacent its upper end a transverse opening 15 adapted to receive the bow of the lock.

The towels 16 used in connection with a rack of the herein described construction are provided, preferably near one of their corners, with eyelets 17 bushed with metal gromets through which the link is inserted.

In the operation of my invention a number of towels are strung on the link by inserting the straight end 12 thereof through the eyelets 17. This is preferably done in the laundry or storeroom from which the clean towels are obtained and after a sufficient number of towels have thus been suspended from the link, the lock is applied to the side thereof opposite to that at which the chain is attached, as shown in Fig. 3, to prevent unauthorized persons from removing the towels.

The links and the towels thus held thereon are distributed among the different lavatories equipped with racks of the construction herein described and each link is secured to the respective rack by first inserting the edge of the shelf thereof through

the entrance 9 of the link and then placing the eye 10 of the link over the stud 6 on the hook 4 while the straight end 12 of the link is lowered through the openings of the shelf 5 and the respective reinforcing plate 8.

To subsequently secure the link against unauthorized removal, the lock 13 is detached from the side of the link to which it was applied to secure the towels in transportation, and its bow is inserted through the aperture 15 in the end of the stud 6 as illustrated in Fig. 2. After the link has thus been secured on the stationary rack the towels may be moved upwardly along the outer portion of the link and piled upon the shelf 3.

After each towel is used it is naturally returned to its suspended position and when all the towels are soiled the link is removed from the rack by reversing the above-explained operation, and another link holding clean towels, is put in its place.

It will thus be seen that by the use of my invention the time-taking work of placing the towels separately on the rack as was required in the use of the device shown in the before-mentioned patent, is entirely avoided and the interchange of clean and soiled towels thereby greatly expedited.

My invention furthermore tends to prevent loss of towels by carelessness or dishonesty of employees of the concern by which the towels are supplied, and the towels connected with the link of the rack by a single eyelet, are more readily adjusted and easier used than those which were secured by two eyelets, as in the prior construction.

Having thus described the construction and operation of my improved towel rack, I desire it understood that if so desired two or more towel holding links may be secured to the same shelf and that other variations in the construction and arrangement of the parts of the rack may be resorted to within the spirit of my invention as set forth in the following claims:

1. A towel-rack comprising in combination, a support including a projecting member provided with an aperture, a stud below said aperture, and a towel-holding link having an entrance to admit said member, said link at one side of said entrance having an end adapted to enter said aperture, and at the opposite side of the same, an eye to receive the stud.

2. A towel-rack comprising in combination, a support including a projecting member provided with an aperture, and a stud in alinement with said aperture, and a towel-holding link having an entrance to receive said member, said link at one side of said entrance having an end adapted to enter said aperture, and at the opposite side of the same, an eye to receive the stud, and

means for locking said link against unauthorized removal from said support.

3. A towel-rack comprising in combination, a support including a projecting member provided with an aperture, and a stud 70 in alinement with said aperture, and a towel-holding link having an entrance to receive said member, said link at one side of said entrance having an end adapted to enter said aperture, and at the opposite side 75 of the same, an eye to receive the stud, said stud having means for the application of a lock whereby to prevent unauthorized removal of the link from said support.

4. A towel-rack comprising in combination, a support including a projecting member provided with an aperture, and a stud 80 in alinement with said aperture, a towel-holding link having an entrance to receive said member, said link at one side of said entrance having an end adapted to enter said aperture, and at the opposite side of the same, an eye to receive the stud, and a chain 85 fastened at one side of the link and adapted to be locked either to the opposite side of the same to prevent unauthorized removal of towels from the link, or to the stud to prevent unauthorized removal of the link from the support.

5. In a towel-holder, a link having a gap 95 for the insertion of one of its ends into the apertures of apertured towels, a support for the link, and an adjustable locking-means which in one of its adjusted positions extends across the link at one side of its gap to prevent the removal of towels strung thereon, and which in another adjusted position coöperates with the support to prevent the removal of the link.

6. A towel-holder comprising a rigid link 105 having a permanent gap for the insertion of one of its ends into the apertures of apertured towels and adapted to separately hold a bunch of towels for carrying them to and from a stationary support, and a support adapted to removably hold said link in a determinate position, a part of said support bridging the gap of the link whereby to prevent the removal of towels from the link and the support when the one is in place 110 on the other.

7. A towel-holder comprising a link having a gap for the insertion of one of its ends into the apertures of apertured towels, a support adapted to hold the link in a determinate position, and adjustable locking means adapted to either coöperate with the support to secure the link against unauthorized removal or to obstruct the removal of towels from the link when it is separated 120 from the support.

8. In a towel-holder, the combination of a link having a permanent gap for the insertion of one of its ends into the apertures of apertured towels, and at one side of said 130

gap, a lateral projection, and a support adapted to hold the link in a determinate position and including a part which coöperates with the projection of the link for 5 the support thereof and which bridges the gap of the link to prevent the unauthorized removal of towels strung thereon.

In testimony whereof I have affixed my signature in presence of two witnesses.

LOUIS STRAUB.
